ATTORNEYS.

UNITED STATES PATENT OFFICE.

HENRY L. HURD, OF BEVERLY, MASSACHUSETTS.

PRESSURE-CYLINDER FOR ENGINES.

1,145,065.

Specification of Letters Patent. Patented July 6, 1915.

Original application filed January 10, 1911, Serial No. 981,268. Divided and this application filed January 4, 1913. Serial No. 740,106.

To all whom it may concern:

Be it known that I, HENRY L. HURD, a citizen of the United States, residing at Beverly, county of Essex, State of Massachusetts, have invented a certain new and useful Improvement in Pressure-Cylinders for Engines, of which the following is a specification, reference being had therein to the accompanying drawings.

10 The invention relates to an improvement in pressure cylinders for engines.

The invention is intended for application to use for controlling link motion engines in which the link can be thrown, or for any 15 movement off of the center which should go back to the central point and stop.

The object of the invention is to actuate the piston in either direction from the center of the cylinder toward the end and to 20 cause it to automatically return to the center and stop whether the cylinder is in either a vertical or horizontal plane.

The invention will be fully understood from the following description taken in connection with the accompanying drawings, 25 and the novel features will be pointed out and clearly defined in the claims at the close of the specification.

In the drawings: Figure 1 is a sectional 30 elevation of a cylinder embodying the invention, showing the piston in central position. Fig. 2 is a sectional elevation of the cylinder showing the piston moved from the central position shown in Fig. 1. Fig. 35 3 is a cross section through the cylinder on line 3—3 of Fig. 2.

In the drawings,—1 represents a cylinder within which is a piston 2 which is normally at the center and which is reciprocally within the cylinder toward either end and back to the center. A piston rod 3 connected with the piston passes through one head of the cylinder, the head being provided with a stuffing box through which the 45 piston rod passes. Connected with the cylinder 1 is a steam chest 4 to which steam is supplied through a pipe 5. Leading from the steam chest 4 into the cylinder 1 is a port 6 to admit steam into the cylinder at 50 or near one end thereof on one side of the piston, and a port 7 leads from the steam chest into the other end of the cylinder. Leading from the cylinder to the steam chest is an exhaust port 8 which cushions 55 the piston when the piston moves to the left-

hand end of the cylinder, as viewed in Fig. 1, and leading from the cylinder to the steam chest is an exhaust port 9 which cushions the piston when the piston moves to the right-hand end of the cylinder, as 60 viewed in Fig. 1.

Within the steam chest is a balanced D slide valve 10 which slides on the face of the steam chest. Within the slide valve are two exhaust cavities 11—12 which respectively connect by means of exhaust passages 13 and 14 with an exhaust pipe 15 leading to the atmosphere. The slide valve 10 is provided with valve stem 16 which passes through the steam chest and may be 70 manually operated from the outside. Any suitable form of balanced connection of well known character may be employed. As shown in the drawings, a pendulum lever 22 is pivotally connected on its upper end 75 at 23 to a fixed support 24, the lower end of said lever being pivotally connected with the stem 16 of the D slide valve through an elongated slot 26. A weight 25 is secured to the lever 22 which tends to hold the lever 80 plumb, and which, when the stem 16 of the valve is released after being moved to the right or to the left from the central position shown in Fig. 1, will swing back to plumb position moving the D slide valve back 85 to central position. Leading through the side of the cylinder are two steam ports 17 connecting with an opening 18 to the atmosphere at the middle of the cylinder. The opening 18 is preferably smaller than the 90 inlets 6 and 7 and is constantly open.

When the slide valve 10 is in the central position as shown in Fig. 1, the admission ports 6 and 7 are both partly open and the exhaust ports 8 and 9 are both closed and 95 the piston 2 is in its central position. If it is desired to move the piston toward the right-hand end of the cylinder, as in Fig. 2, in which it is shown part way toward the end, the valve 10 should be moved to the 100 right from the position shown in Fig. 1 by means of the valve stem 16 which will be operated by hand of the operator at such time as he desires to move the piston. By this movement of the valve stem 16 the slide 105 valve 10 is moved whereby the steam passage 6 is opened fully and the steam passage 7 is closed and the exhaust passage 9 is opened to the atmosphere through the exhaust cavity 12 and the exhaust passage 14. This re- 110

lieves the pressure from the right-hand end of the piston 2 so that the piston will be moved to the right-hand end of the cylinder by the pressure on the left-hand end. The 5 relief outlet 18 being of smaller diameter than the inlet 6 there will be pressure enough in the left-hand chamber of the cylinder to swing the piston 2 to the right. The relief ports 17 and 18 being left open, 10 the steam in the left hand end of the cylinder will gradually pass out and reduce the pressure. As soon as the stem 16 is released after the valve 10 has been moved to the right by hand, as already described, the 15 weight 25 will automatically swing back to plumb, thereby moving back the stem 16 and moving the valve 10 back to its central position as shown in Fig. 1, so that steam ports 6 and 7 will both partly open, and 20 admit pressure to the cylinder on both sides of the piston 2. By reason, however, of the exhaust ports 17, 18, the pressure on the left-hand end of the piston will be released so that the pressure on the right-hand end 25 of the piston 2 will drive the piston back to the center. The movement of the piston to the center will be slowed down toward the end of its movement by reason of the piston rings closing successively the openings 30 17-17. The piston will remain at the center with the pressure equalized until the slide valve is again operated by hand. If it is desired to drive the piston to the right again, the relief valve 27 should be closed and the 35 rod 16 will be again pulled to the right, as already described. If it is desired to drive the piston to the left the slide valve 10 will be moved by hand as already described farther to the left so as to close the steam 40 passage 6 and fully open the steam passage 7, thus bringing the pressure against the right-hand end of the piston and exhausting the pressure on the left-hand end of the piston through the exhaust cavity 11 and 45 exhaust passages 13-15. When the hand is released from the rod 16 the slide valve 10 will be brought back to the center again automatically, as already described, by reason of the balanced connection, and the pressure upon the right-hand end of the piston 50 will be exhausted through ports 17, 18, allowing the pressure which comes in through the lead passage in the partly opened inlet 6 to drive the piston back to center where it 55 will again stop, as already explained.

The number of the exhaust passages 17 will depend upon the size of the cylinder. For a small size cylinder one passage may be sufficient. The exact number is not essential.

19 represents the cross head with which the piston rod 3 is connected, and 20 represents a guide rod on which the cross-head 19 slides for the purpose of steadyng.

65 21 represents a link connected with the

cross-head through which the motion is transmitted to the mechanism which it is desired to operate. In the drawings the link 21 is shown as connected with a crank 27 which actuates a throttle valve 28 of an engine 29. The movement of the rod 3 and link 21 to either the right or left from the center will open the throttle valve and the movement of the piston 2 back to center will close the throttle valve 28. When employed to operate a throttle valve the most efficient results are obtained by so constructing and proportioning the parts that the link 21 will move at each stroke far enough to swing the crank 27 through an arc of about 50 70 degrees. The operation of a throttle valve, however, is only one form of adaptation of the invention. It is obvious that my invention can be utilized to drive various forms of apparatus other than a throttle valve in 75 which reciprocating movement is desired by making suitable connection with the link 21. 80

The reason for providing the cylinder with separate exhaust and separate steam ports at each end of the cylinder is so that when the piston closes one of the exhaust ports the steam which is thereby held acts as a cushion to the piston on that end of the cylinder. 90

While it is possible to operate the piston 95 so that it can be brought back to center without the use of exhaust ports, yet the exhaust ports render the device much more efficient, especially in speed.

One of the uses to which my invention 100 may be applied is in connection with engines employed in operating trolley boom swingers for unloading cargoes, such for instance as shown in Patent No. 981,268, issued to me January 10, 1911. 105

What I claim is:

1. A cylinder, a piston which is normally at the center of the cylinder and is movable within said cylinder toward and from either end, a rod connected with said piston and extending through one of the heads of the cylinder, means for admitting fluid pressure to and means for exhausting it from said cylinder at opposite ends thereof, means whereby when the fluid pressure is admitted at one end it may be exhausted at the other end whereby said piston is reciprocated in either direction, a relief port which is closed by the piston when at the center and which is opened by movement of the piston away from center thereby automatically relieving the pressure from that side of the piston which is toward the center and whereby the pressure on the other side drives the piston back to the center. 110 115 120

2. A cylinder, a piston which is normally at the center of the cylinder and is movable within said cylinder, a rod which is connected with said piston and extends through one of the heads of the cylinder, a source of 125 130

fluid pressure having connection with both ends of said cylinder, exhaust ports at each end of said cylinder, valve mechanism which controls the admission to and exhaust from 5 both ends of said cylinder, said valve being normally in position where it closes the exhaust ports at both ends and leaves open the inlets at both ends, thereby equalizing the pressure and retaining the piston at the 10 center, means whereby at the will of the operator said valve mechanism may be operated so that fluid pressure may be admitted to either end and shut off from the other end, and the exhaust opened from that end 15 from which the admission is shut off and closed from the other end whereby the said piston is moved from the center toward the opposite end from that in which the inlet port is open and means whereby when the 20 said valve has been moved to either end it is immediately and automatically moved back to center where it closes both exhaust ports and leaves open the inlet ports at both ends and thus equalizes the pressure which 25 thus holds the piston at the center.

3. A cylinder, a piston which is normally at the center of the cylinder and is movable within said cylinder, a rod which is connected with said piston and extends through 30 one of the heads of the cylinder, a source of fluid pressure having connection with both ends of said cylinder, exhaust ports at each end of said cylinder, a relief port at the center which is closed by the piston when 35 at the center and which is opened by movement of the piston away from the center, valve mechanism which controls the admission to and exhaust from both ends of said cylinder, said valve being normally in position 40 where it closes the exhaust ports at both ends and leaves open the inlets at both ends, thereby equalizing the pressure and retaining the piston at the center, means whereby at the will of the operator said valve mechanism 45 may be operated so that fluid pressure is admitted to either end and shut off from the other end, and the exhaust is opened from that end which is shut off and closed from the other end whereby the said piston 50 is moved from the center toward the opposite end from that in which the inlet port is open, and means whereby when the said valve has been moved to either end it is immediately and automatically moved back to center where it closes both exhaust ports and leaves open the inlet ports at both ends and thus equalizes the pressure and retains the piston at the center.

4. A cylinder, a piston movable within 60 said cylinder, a piston rod connected with said piston and extending through one of the heads of the cylinder, a steam chest hav-

ing a steam inlet thereto and having steam passages leading into opposite ends of the cylinder, the cylinder having separate exhaust ports leading back to the steam chest, said steam chest having two separate exhaust passages leading to the outside atmosphere, valve mechanism which is adapted to open and close said steam and exhaust 65 ports, means whereby the valve mechanism may be operated to open the inlet port and the exhaust port connecting the steam chest with one end of the cylinder and to close the inlet and open the exhaust to the other 70 end of the cylinder and also adapted to open both the inlet ports and close both the exhaust ports, and a relief passage at the middle of the cylinder which is closed by the piston when the piston is in its central 75 position and which is opened when the piston moves from the center to either end, said valve being normally at the center position closing both exhaust ports and leaving open both inlet ports, and means for automatically moving said valve back to said central position immediately after it has moved to either end of the cylinder.

5. A cylinder, a piston movable within said cylinder, means for admitting fluid 90 pressure to and means for exhausting it from said cylinder at opposite ends thereof, means whereby when the fluid pressure is admitted at one end it may be exhausted at the other end, whereby said piston is moved 95 in either direction, said cylinder having a relief passage which is closed by the piston when at the center and which is opened by the movement of the piston away from the center thereby relieving the pressure from 100 that side of the piston which is toward the center, whereby the pressure on the other side drives the piston back to the center.

6. A cylinder, a piston movable within said cylinder, means for admitting fluid 105 pressure to and means for exhausting it from said cylinder at opposite ends thereof, means whereby when the fluid pressure is admitted at one end it may be exhausted at the other end, whereby said piston is moved 110 in either direction, said cylinder having a relief passage which when the piston is away from the center relieves the pressure from that side of the piston which is toward the center, whereby the pressure on the other side drives the piston to the center, said relief passage being closed by the piston when 115 it is at the center.

In testimony whereof I affix my signature, in presence of two witnesses.
